UNITED STATES PATENT OFFICE

113,189

DESIGN FOR A DRESS

Albert Ruchman, New York, N. Y.

Application December 5, 1938, Serial No. 81,568

Term of patent 3½ years

To all whom it may concern:

Be it known that I, Albert Ruchman, a citizen of the United States, residing at 1359 Broadway, New York, N. Y., in the county of New York and State of New York, have invented a new, original, and ornamental Design for a Dress, of which the following is a specification, reference being had to the accompanying drawing, forming part thereof.

Fig. 1 is a front view of a dress showing my design;

Fig. 2 is a rear view of the dress shown in Fig. 1, and

Fig. 3 is a view of the sleeve of the dress shown in Fig. 1 as seen from the side.

The characteristic feature of my design resides in the combination on the V necked dress disclosed of the specific puff stitched embroidery on the sleeves and on the dress front between the shoulder and waist yokes as shown.

I claim:

The ornamental design for a dress, substantially as shown and described.

ALBERT RUCHMAN.
